UNITED STATES PATENT OFFICE.

SIMEON C. LAWLOR, OF DULUTH, MINNESOTA, ASSIGNOR, BY DIRECT AND MESNE ASSIGNMENTS, TO LAWLOR'S SAFETY WINDOW CLEANER COMPANY, OF MINNEAPOLIS, MINNESOTA, A CORPORATION.

WINDOW-WASHING APPARATUS.

SPECIFICATION forming part of Letters Patent No. 698,030, dated April 22, 1902.

Application filed July 17, 1900. Serial No. 23,948. (No model.)

To all whom it may concern:

Be it known that I, SIMEON C. LAWLOR, a citizen of the United States, residing at Duluth, in the county of St. Louis and State of Minnesota, have invented certain new and useful Improvements in Window-Washing Apparatus; and I do hereby declare the following to be a full, clear, and exact description of the invention, such as will enable others skilled in the art to which it appertains to make and use the same.

This invention relates to improvements in window-cleaners, and particularly to that class of such devices by means of which the outer surfaces of the window may be cleaned by a person operating inside of the house, whereby the exposure and danger of falling from the window-sill is avoided, the object of the invention being to provide an improved device of this class by which the desired operations may be performed in the least possible time and with the least possible expenditure of labor.

With this object in view the invention consists in an improved window-cleaner of the class mentioned, the construction, arrangement, and combination of the parts of which will be hereinafter fully described and afterward specifically set forth in the claims.

In the accompanying drawings, Figure 1 is a vertical sectional view through a window-washer constructed in accordance with my invention, the section being taken on the plane indicated on the line 1 1 of Fig. 2. Fig. 2 is a vertical section through the same on a plane at right angles to that of Fig. 1 and parallel with a window-pane, as indicated by the broken line 2 2, Fig. 1. Fig. 3 is a detail perspective view of the swiveled carriage.

Like numerals of reference mark the same parts wherever they occur in more than one view of the drawings.

Referring to the drawings by numerals, 4 indicates a hollow vertical standard, which in the actual operation of the device stands outside of the window. This standard may or may not be closed at the bottom, as shown, and is provided with a pulley 5, journaled in notches or slots at its upper end.

6 indicates a rubber cord or tube secured

at its lower end in the lower end of the vertical standard by any suitable means and passed upward through the standard and over the pulley 5, the opposite end of the cord being secured to a block 7, mounted to 55 slide vertically upon the standard 4 and carrying a brush or other washing or cleaning device 8 in contact with a window-pane 9.

10 indicates a cord secured to the lower side of the block 7 and passed downward under a 60 pulley 11, journaled in bearings in a block 12, mounted on the lower portion of the standard 4 and secured thereon by a set-screw 13 or other suitable means. From the pulley 11 the cord 10 passes inward and terminates in 65 a position within ready reach of the hand of the person within the room.

14 indicates a horizontal tube or bar secured in the block 12 at a right angle to the standard 4 and to the window-pane 9, which 70 tube or bar projects inward under the window-sash and is provided at its inner end with a suitable handle 15.

16 indicates a horizontal tube adapted to be secured between the sides of the window-frame, as at 17, below and parallel with the bottom bar of the window-sash and near the sill of the window. This bar or tube 16 is secured in such position by means of springs 17, bearing at their inner ends against a plug 75 18 in the tube 16 and at their outer ends against an enlarged head 19 on each of the screw-rods 20, which are provided with roughened or padded heads 21 to bear against the sides of the window-frame, nuts 22 being provided on 80 the threaded bars to tighten them in position. Upon the tube 16 is mounted a carriage 23, in this instance consisting of a hollow or tubular structure, carrying on its lower side a projection 24, having a flat lower face. Swiveled to 90 the carriage 23 is a block 25, having its upper face flattened to engage the flat lower face of the projection 24, before mentioned, and free to turn on the swiveling pin 26. This block 25 is bored to receive the tube 14, before mentioned, which tube is secured therein at any desired position by a set-screw 27 or other suitable means.

In the operation of the device when the parts are adjusted as before described the 100

operator within the room by drawing inward on the cord 10 causes the block 7 to slide downward on the vertical standard 4, drawing the brush or cleaner 8 downward on the pane 9 of the window. Upon the release of the cord 10 the rubber cord or tube 6 by its elasticity causes the block 7 to slide upward on the standard 4, thus moving the brush or cleaner 8 upward on the window-pane. The carriage 23 being movable horizontally on the tube 16, the bar or tube 14 and vertical standard 4, with the brush or cleaner 8, may be moved laterally to clean an adjacent portion of the window in the same manner, and this lateral adjustment may be repeated until all parts of the pane have been cleaned. The provision of the swiveling adjustment between the block 25 and the carriage 23 is of importance in some instances to more easily reach all parts of the window-pane, and especially to clean any slight strip which may have been left between the portions of the pane cleaned during each lateral adjustment of the washing mechanism on the tube 16.

25 The provision of the rubber cord or tube 6 is of special importance, for the reason that the material thereof is not subject to damage by moisture, as would be a metal spring, and for the further reason that the structure is simplified and cheapened, the rubber cord or tube serving both as a spring to return the block 7 upward and also as a cord to properly work over the pulley 5.

I make no specific claim under this application to the construction of the coupling, which is fixed upon the vertical standard and receives and holds the laterally-movable horizontally-extending window-washing rod, nor do I make any specific claim under this application to the construction and arrangement of the carriage carrying the horizontally-extending laterally-movable window-washing

rod, as the same are made the subject of an application filed by me on the 26th day of June, 1900, Serial No. 21,699. 45

Having thus described the invention, what is claimed as new, and desired to be secured by Letters Patent, is—

1. In a window-washer, the combination of a horizontal tube adapted to be rigidly secured between the sides of the window-frame, of a carriage mounted to slide on said tube, a block swiveled to said carriage, a horizontal tube or bar mounted in said swiveled block, a vertical standard carried by the horizontal tube or bar, and washing devices carried by the vertical standard, substantially as described. 50

2. In a window-washer, the combination of a vertically-arranged hollow standard, a pulley mounted at the upper end thereof, a block slidably secured on the outside of the standard and carrying a window brush or cleaner which always remains outside of the standard, an elastic cord fixedly secured at or near the lower end of the standard and extending upwardly therefrom along said standard and passed over the pulley and secured to the under side of the block for automatically raising said block and the brush or cleaner carried thereby each time they are drawn downwardly by the operator, and an inelastic cord secured to the under side of the block and extending to a suitable point within easy reach of the operator for drawing the block downward on the standard, substantially as described. 60

In testimony whereof I hereunto affix my signature in presence of two witnesses.

SIMEON C. LAWLOR.
